United States Patent Office

Des. 184,433
Patented Feb. 17, 1959

184,433

UNIVERSAL TEST STAND FOR ENGINES OR SIMILAR ARTICLE

Arnold M. Goetze, Battle Creek, Mich.

Application September 9, 1955, Serial No. 37,867

Term of patent 14 years

(Cl. D26—1)

Figure 1 is a front perspective view of a universal test stand for engines or similar article, showing my new design;

Figure 2 is an end perspective view; and

Figure 3 is a rear perspective view thereof.

I claim:

The ornamental design for a universal test stand for engines or similar article, substantially as shown.
